United States Patent Office.

GEORGE FAY, OF NEWTON, MASSACHUSETTS, ASSIGNOR TO HIMSELF, J. HENRY SIMONDS, AND HENRY CHASE.

Design No. 3,157, dated August 11, 1868.

DESIGN FOR ADVERTISING-PANEL.

The Schedule referred to in these Letters Patent and making part of the same.

TO ALL WHOM IT MAY CONCERN:

Be it known that I, GEORGE FAY, of Newton, in the county of Middlesex, and State of Massachusetts, have invented or produced a new and original Design for Ornamental or Decorative Advertisements, of which the following is a full, clear, and exact description, reference being had to the accompanying drawings, forming a part of this specification.

The object of my invention is to produce an ornamental design for advertising, to be affixed permanently to the wall of a public house, hotel, railroad-station, or other public place, and which shall so combine objects of art with a system of advertisements as to render the same attractive to the eye.

My design is intended to form one of a series of panels of a wall, or it may be made to cover the entire wall or side of a room; and it consists of a border, formed of a plane surface, *a a*, surrounded by an ornamentation, *i i*, as shown in the drawings.

Below the border is a representation of a panelling, *b*. In the centre, *c*, of the upper portion, is a space for the representation of a picture, painting, or work of art, and occupying the spaces indicated by *d d*, &c., are smaller pictures, as shown. The remaining spaces, *e e*, are to be occupied by advertisements.

The whole may be either attached to or impressed upon a sheet or roll of paper, cloth, or what is known as the wood-hangings, or be painted in fresco.

What I claim as new, and desire to secure by Letters Patent, is—

The design for a panel for decorative advertising, as herein shown and described.

In testimony whereof, I have signed my name to this specification in the presence of two subscribing witnesses.

GEORGE FAY.

Witnesses:
